SPINDLE

Robert Leclercq, Lille, France

Application March 25, 1937, Serial No. 133,043
In Belgium March 30, 1936

4 Claims. (Cl. 118—63)

The present invention has for its object an independent spinning spindle with a reversed flyer, that is to say, a spindle adapted to be mounted on a frame without necessitating the precise regulation of a number of parts of the frame, since such a spindle comprises a fixed support, all the guiding parts and means for perfect lubrication.

This spindle has a braked bobbin support and a device for the automatic hooking of the thread for fresh bobbin formations.

The invention has for its object the formation of bobbins on opened out metallic tubes.

Such a spindle, with all its accessories, constitutes an independant unit operating in a semi-automatic manner and adapted to be arranged on a spinning frame and preferably on a frame for spinning wet flax.

The accompanying drawing shows diagrammatically by way of nonrestrictive example, one method of carrying out the invention.

There is shown in Figure 1 the assemblage of the parts which constitute a spinning spindle, Figure 2 shows to a larger scale, the support of the tube, the tube itself as also the device for hooking on the thread.

The parts which constitute this device for hooking on the thread are shown in perspective in Figures 3 and 4.

A spindle thus constructed may be easily mounted, avoids all vibration whilst working and permits the placing in position of the tubes and the instantaneous removal of the bobbins, it resists perfectly the action of water and is consequently particularly suitable for wet spinning.

The spindle 1 shown on the annexed drawing cannot rotate owing to known methods of guiding and for example, by the arrangement of flat parts at its base at 2, it is given a rising and falling movement by members to which it can be loosely connected and it moves in a socket 3 which forms the casing of the spindle and which can be fixed, owing to a collar 4 and a nut 5, on to the frame of a spinning machine.

The upper outer part of this socket serves as a guide for the rotating part 6 which receives this movement by any known means, for example, by the intermediation of a pulley 8.

At its extremity the spindle serves as a support for a part in the form of a cup 15 which is fixed thereon by keys or by any other suitable means. It then serves as the axis of rotation for a part 16 on which can be placed the tube 17. The lubrication of this part is ensured by the introduction of lubricant into a cup 18 provided at the upper part of the spindle.

The tube support 16 carries at its lower part an inverted cup 29 which protects a washer 19 the material and dimensions of which are chosen according to the amount of brake effect desired. This washer 19 rests on a disc 20, preferably metallic, disposed over the part 15 and secured thereto.

The part 17 on which the bobbin forms, is constituted by a metallic tube held to the rotating support by one or more springs 21 of known design and shape.

The tube support 16 is secured to the spindle by means of one or more lock projections 22 urged inwardly, by an elastic collar 23, into a channel 24 provided in the spindle itself. As will be seen from Figure 2, it is impossible to disengage these projections from the channel as long as a tube is arranged on this support for the formation of a bobbin.

For the automatic engagement of the thread 20 the cup 15 carries hooks 25 as shown in Figure 3, while Fig. 4 shows a member 26 having teeth 27 which is adapted to be held between 29 and the tube 17.

The thread, which is passed through the hook 28 of flyer 1, first engages the teeth 25 when the spindle is raised and the tube 17 empty. A few turns of thread are then wound around said tube which, gradually, starts to revolve. Since the hollows of the hooks are in a plane below the member 26, the thread continues to wind around the central boss of 26; this winding produced at a time when the tube revolves slowly serves as a starting point for the bobbin proper. As soon as the tube starts to revolve rapidly, the centrifugal force projects the free end of the thread from the boss of 26; this end is removed with the bobbin on completion thereof.

These spindles, free from vibration, will permit the rapid equipment of spinning frames without difficulty, the production of which will be increased.

Having now particularly described and ascertained the nature of my said invention, and in what manner the same is to be performed, I declare that what I claim is:

1. In a reversed flyer spinning spindle, a spindle shaft, a circumferentially toothed cup-like member secured to said spindle, a concentric tubular tube support frictionally connected with the cup-like member, a disc within the cup-like member and associated with the tubular support, a tube frictionally engaged with said support and resting over the disc, and means for winding thread over said tube.

2. In bobbin winding mechanism including a spindle, a cup secured to said spindle, said cup having teeth formed therein laterally, a tube support concentrically over the spindle and having a lower flange resting within the cup over friction material, a toothed disc resting over said flange above the teeth of the cup, a bobbin tube frictionally retained over the support above the disc, and a reversed flyer for winding thread onto 10 the tube.

3. In a spinning spindle having a non-rotary spindle and a reversed flyer, thread hooking means secured to the spindle, a thread covering

disc disposed within the hooking means, a tube support resting over the hooking means and concentrically around the spindle, and a tube frictionally engaged to the support for receiving the thread. 5

4. A reversed flyer spinning spindle, comprising the spindle shaft proper, a toothed cup-shaped member secured to said shaft, a tube support concentric to the shaft and resting on the cup bottom, a thread covering disc within said cup 10 at a level with the cup's teeth, and a bobbin tube frictionally engaged over the support.

ROBERT LECLERCQ.
